UNITED STATES PATENT OFFICE.

JUAN N. SILVA, OF PUEBLO, COLORADO.

KILN.

1,192,946.

Specification of Letters Patent. Patented Aug. 1, 1916.

Application filed August 28, 1915. Serial No. 47,838.

To all whom it may concern:

Be it known that I, JUAN N. SILVA, a citizen of the Republic of Mexico, residing at Pueblo, in the county of Pueblo and State of Colorado, have invented new and useful Improvements in Kilns, of which the following is a specification.

This invention relates to kilns and constitutes an improvement upon Letters Patent granted to me March 23, 1915, Number 1,133,190, the main object of the invention being to produce a battery or several batteries of kilns all connected up in a system comprising one or more series of kilns so combined and arranged with relation to each other and a system of flues and tunnels, combined with exhaust and blast fans, that the heat or products of combustion exhausting from one kiln, for example, may be utilized in one or more succeeding or adjacent kilns for drying out purposes thereby producing a multiple kiln which under the arrangement of flues hereinafter described forms what may be termed a semi-continuous system giving practically the same service and economy as the present continuous kiln while being easier to operate and of a more simple construction.

The most economical kiln now in use is known as the continuous kiln but the cost is so increased relatively to the ordinary kiln that the price is prohibitive in a majority of cases. The cost of the continuous kiln is from eight to twenty times as expensive as the ordinary common kiln the chief advantage of the continuous kiln residing in the fact that the waste heat is reduced to a minimum while in the ordinary type of kiln from fifty to seventy per cent. of the heat passes out through the stack. By the arrangement and system hereinafter explained, a plant employing the ordinary form of kiln may be easily and economically converted into the improved form so as to produce a continuous or semi-continuous system that may be operated as cheaply as a standard continuous kiln.

With the above and other objects in view, the invention consists in the novel construction, combination and arrangement of parts, as herein described, illustrated and claimed.

In the accompanying drawings:—Figure 1 is a diagrammatic view showing two batteries or series of kilns, including the main exhaust and air feed tunnels, the blast and exhaust fans, and the kiln connecting flues.

Fig. 2 is a horizontal section through a pair of adjacent kilns taken on the level of the fire boxes. Fig. 3 is a vertical diametrical section taken centrally of Fig. 2. Fig. 4 is an enlarged vertical section through one of the fire boxes including the ash pit, grate and air distributor. Fig. 5 is a plan view of one of the grates.

As all of the kilns of the system embody the same general construction and arrangement, a description of one will answer for all. Each kiln is designated generally at A and is shown as of the circular wall type, said main circular wall being indicated at 1 and being of any suitable height and covered by a crown wall 2. The lower portion of the wall 1 is considerably thickened as shown at 3 to provide for the construction therein of a fire box 4 beneath which is arranged a grate designated generally at B while beneath the grate is an ash pit 5 having a removable ash pan 6 and a door 7 through which the ash pan 6 may be withdrawn and replaced.

In communication with each fire box or furnace 4 is a vertically extending bag wall 8 forming a substantially vertical flue 9 through which the products of combustion may pass upwardly or downwardly as the case may be, the movement of the current of the products of combustion being controlled by means to be hereinafter described. These bag walls and flues are arranged in a circular series around the interior of the circular wall 1 of the kiln so as not to interfere with one or more door ways 10 through which the material to be burned may be introduced and removed. The floor 11 of the kiln is formed with openings 12 extending through the floor and communicating with a main diametrically extending flue 13 located under floor 11 and inwardly converging branch flues 14 which extend from the circular wall 1 inwardly and communicate with the main flue 13. The flue 13 extends from kiln to kiln and serves to transfer the products of combustion from one kiln to another so that the products of combustion after being used for burning the material in one kiln may be transferred or exhausted to an adjacent kiln or kilns for the purpose of primarily heating the material therein.

Parallel to the kiln connecting flue 13 is an exhausting flue 15 which extends throughout the series of kilns so as to carry the products of combustion finally to an outlet

stack 16 located at any convenient point in the plant. Between adjacent kilns the flue 13 is provided with dampers 17 and 18 arranged in spaced relation to each other and 5 the flue 15 is provided with correspondingly arranged dampers 19 and 20. Between the dampers of the flue 13 and the dampers of the flue 15 is arranged a transfer damper or valve 21 whereby the contents of one of the 10 flues 13 or 15 may be directed into the other flue of the pair. The said dampers also enable any kiln to be cut off from the adjacent kilns at opposite sides thereof.

In view of the arrangement of the valves 15 17, 18, 19, 20 and 21 as shown, for example, in Fig. 2, by closing the valve 18 and leaving the valve 17 open and by closing the valve 19 and opening the valve 20, the products of combustion from the 20 left hand kiln may be transferred by opening the valve 21 to the exhaust flue 15 so as to pass by the next adjacent right hand kiln and either on to the atmosphere or into any succeeding kiln desired. In 25 other words, the flue 15 is used for the purpose of carrying the products of combustion past one or more kilns as may be desired in accordance with the condition of the contents of the kilns at any particular time.

30 The flue 15 is not connected directly with or to the bottoms of the kiln; the only connection said flue 15 has with the kilns is through the flue 13 by way of the damper 21. As there are many varieties of clays, requiring different treatment as to heating, as 35 well as cooling, the flue 15 is provided to do such work, serving to draw the gases from any kiln and direct the same to any other desired kiln or kilns in the battery wherever 40 needed. The flue 15 is also to be used in case it is necessary to draw the products of combustion from any particular kiln to any other kiln for drying purposes, without interfering with any kiln or kilns that may 45 be between the kiln in full fire and the kiln in which the drying operation is progressing. The connection of the flue 15 to the smoke stack is to be used in case there should be more waste heat than could be utilized; 50 in such case the surplus heat may be discharged to the stack thus providing for the necessary outlet for the products of combustion of the kiln or kilns. In other words, the flue 15 is designed to carry the heat from 55 any part of the battery of kilns to any other point or unit of the battery where it is needed, while the flue 13 is only to conduct the heat directly from one kiln to the next.

60 In connection with the series of kilns I employ a main exhaust tunnel 22 and a main air feed tunnel 23. Air is forced through the tunnel 23 by means of a blast fan 24 into a circular or manifold flue 25 one of which encircles each of the kilns A, the end portions 65 26 and 27 of said manifold flue being

extended outwardly so as to communicate one with the air feed tunnel 23 and the other with the main exhaust tunnel 22. A damper or cut off 28 controls the terminal portion 26 of the circular manifold 25 and a similar 70 damper or cut off 29 controls the other end portion 27 of said circular manifold. Therefore, by opening the valve 28, air under pressure may be forced through the manifold 25 into the furnaces and thence upwardly 75 through the bag walls 9 into the top of the kiln, the products of combustion passing therefrom downwardly through the openings 12 in the floor and into the main kiln connecting flue 13 thence into the adjoining 80 kiln by opening the dampers 17 and 18. In the latter kiln the movement of the products of combustion is reversed, the same passing upwardly through the openings in the floor and downwardly through the bag walls 8 and 85 through tubes 30 which extend under the fire pits into the adjacent circular manifold 25. If it be desired to carry off the products of combustion at this point, the damper or cut off 29 is opened and the other damper or cut 90 off 28 is closed. Thus the products of combustion are drawn into the main exhaust tunnel 22 by the action of an exhaust fan 31 which is shown as arranged at the discharge end of the exhaust tunnel 22 and adjacent to 95 the stack 16 with which the exhaust fan casting connects as shown at 32. The flues 15 above referred to also communicate with the main exhaust tunnel 22 at the point 33.

The grate comprises a substantially rectangular open center frame 34 having arranged in fixed relation thereto an air chamber 35 air to which is supplied by means of a branch pipe 36 leading off from the pipe 30. The top wall or cap 37 of said air chamber 100 is perforated as shown to form an air distributor and at opposite sides thereof are arranged grate bars 38 carried by rock shafts 39 which have bearings in the inner and outer bars of the frame 34, said rock shafts projecting outwardly at one end to receive one or more operating cranks by means of which the grate bars may be rocked to clean the fire. A yoke 40 extends between the projecting ends of the rock shafts, being formed at its 105 opposite ends with loops 41 which embrace said rock shafts, each loop being formed with a hole to receive a pin 42 whereby the rock shafts and the grate bars may be prevented from turning. By removing the pins 41, the 110 grate bars are free to be rocked by means of the hand cranks referred to.

The air chamber 35 is provided in its under side with an air port 42' which is covered by a plate or damper 43 having an opening 125 therein which receives a bolt 44 extending downwardly from the distributor 37 and having threaded thereon an adjusting nut 45. By tightening the nut 45, the plate 43 may be forced tightly against the air chamber so 130

as to close the opening 42' and by loosening the nut 45 the opening 42 may be uncovered so as to allow air to pass therethrough to subsequently pass upwardly through the grate to promote combustion. 46 designates a cut off for the branch pipe 36 above referred to, said cut off 46 being provided with a stem 47 extending outwardly and projecting beyond the frame 34 of the grate so that by sliding 10 said stem inwardly or outwardly the cut off 46 may be opened or closed. 49 designates the fire box door.

From the foregoing description, taken in connection with the accompanying drawings, 15 it will now be understood that the products of combustion after performing their burning operation in one of the kilns may be conducted through the flue 13 to the adjacent kiln or kilns so as to primarily heat the con-

20 contents thereof preparatory to starting the furnaces of the last named kiln or kilns thereby greatly economizing in the consumption of fuel. The circulation is forced by means of the arrangement of flues and tunnels herein-

25 above described when taken in connection with the blast and exhaust fans in the relation thereto as specified. Each circular manifold 25 is thereby adapted to perform two functions, first to conduct a forced draft of air to the furnaces, and secondly to exhaust 30 the products of combustion from said circular manifold. In the left hand kiln in Fig. 3, the air is being forced inwardly through the circular manifold 25 and thence through

35 the air distributors 37 into the space above the grate carrying with it the products of combustion upwardly through the bag walls 8 into the top of the kiln and thence downwardly through the floor into the flues 13 and

40 14. From this point the products of combustion are carried by means of the flue 13 from the left hand kiln to the right hand kiln where they pass upwardly through the floor to the top of the kiln and thence downwardly through the bag walls 8 and the tubes 30 into the circular manifold 25 of the right hand kiln. From this manifold flue, by 45 opening the damper 29, the products of combustion are drawn into the main exhaust tunnel 22 and forced by the fan 31 to the stack 16 from which they pass to the atmosphere.

When a fire is to be built in a furnace of the kiln, the pipe 30 must be closed by means of a stopper 31' which covers the upper end 50 of said pipe, in order to cut off the passage of air therethrough and force the air through the grate.

Having thus described my invention, I claim:—

55 1. The combination of a plurality of kilns, a main air feed tunnel common to all of the kilns, a main exhaust tunnel common to all of the kilns, a combined air feed and exhaust manifold encircling each of the kilns and communicating at one end with the main air

feed tunnel and at the other end with the main exhaust tunnel, and means for cutting off communication between said manifold and the air feed tunnel and also between said manifold and the exhaust tunnel. 70

2. The combination of a plurality of kilns, a main air feed tunnel common to all of the kilns, a main exhaust tunnel common to all of the kilns, a combined air feed and exhaust manifold encircling each of the kilns and communicating at one end with the main air feed tunnel and at the other end with the main exhaust tunnel, means for cutting off communication between said manifold and the air feed tunnel and also between said manifold and the exhaust tunnel, and a kiln 75 connecting flue for transferring the products of combustion from one kiln to an adjoining kiln. 80

3. The combination of a plurality of kilns, a main air feed tunnel common to all of the kilns, a main exhaust tunnel common to all of the kilns, a combined air feed and exhaust manifold encircling each of the kilns and communicating at one end with the main air feed tunnel and at the other end with the main exhaust tunnel, means for cutting off communication between said manifold and the air feed tunnel and also between said manifold and the exhaust tunnel, and a kiln 85 connecting flue for transferring the products of combustion from one kiln to an adjoining kiln, said connecting flue being provided with dampers for the purpose specified. 90

4. The combination of a plurality of kilns, a main air feed tunnel common to all of the kilns, a main exhaust tunnel common to all of the kilns, a combined air feed and exhaust manifold encircling each of the kilns and communicating at one end with the main air feed tunnel and at the other end with the main exhaust tunnel, means for cutting off communication between said manifold and the air feed tunnel and also between said manifold and the exhaust tunnel, bag walls 95 arranged interiorly of the kiln, and pipes extending from said bag walls to the manifold flue. 100

5. The combination of a plurality of kilns, a main air feed tunnel common to all of the kilns, a main exhaust tunnel common to all of the kilns, a combined air feed and exhaust manifold encircling each of the kilns and communicating at one end with the main air feed tunnel and at the other end with the main exhaust tunnel, means for cutting off communication between said manifold and the air feed tunnel and also between said manifold and the exhaust tunnel, furnaces 110 arranged in a circular series in the kiln wall, grates in said furnaces, an air distributing chamber in each grate, and pipes leading from the manifold flue to said air chambers. 115

6. The combination of a plurality of kilns, a main air feed tunnel common to all of the 120

4
kilns, a main exhaust tunnel common to all of the kilns, a combined air feed and exhaust manifold encircling each of the kilns and communicating at one end with the main air feed tunnel and at the other end with the main exhaust tunnel, means for cutting off communication between said manifold and the air feed tunnel and also between said manifold and the exhaust tunnel, furnaces arranged in a circular series in the kiln wall, grates in said furnaces, an air distributing chamber in each grate, pipes leading from the manifold flue to said air chambers, and cut-offs for said air pipes.

15 7. The combination of a plurality of kilns, a main air feed tunnel common to all of the kilns, a main exhaust tunnel common to all of the kilns, a combined air feed and exhaust manifold encircling each of the kilns and

communicating at one end with the main air feed tunnel and at the other end with the main exhaust tunnel, means for cutting off communication between said manifold and the air feed tunnel and also between said manifold and the exhaust tunnel, furnaces arranged in a circular series in the kiln wall, grates in said furnaces, an air distributing chamber in each grate, pipes leading from the manifold flue to said air chambers, cut-offs for said air pipes, said air chamber being provided with an opening, and a movable closure for said opening.

In testimony whereof I affix my signature in presence of two witnesses.

JUAN N. SILVA.
